Specification for Design.

Patented Dec. 9, 1919.

Application filed March 24, 1919. Serial No. 284,870. Term of patent 3½ years.

To all whom it may concern:

Be it known that I, CHARLES E. GAMBILL, a citizen of the United States, residing at Oak Park, county of Cook, and State of Illinois, have invented a new, original, and ornamental Design for a Casing and Frame for a Power and Lighting Plant, of which the following is a specification, reference being had to the accompanying drawings, forming a part hereof, in which—

Figure 1 is a front perspective view of a

power and lighting plant in accordance with the design; and Fig. 2, a rear perspective view of the same.

I claim:

The ornamental design for a casing and frame for a power and lighting plant, as shown.

CHARLES E. GAMBILL.
